UNITED STATES PATENT OFFICE

2,149,513

POWER TRANSMISSION

Emanuel Fischbach, New York, N. Y.

Application June 6, 1938, Serial No. 212,005

1 Claim. (Cl. 74—221)

This invention relates generally to sewing machines, and more particularly it relates to an arrangement for transmitting power to sewing machines.

5 In industrial installations it is customary to arrange power driven sewing machines in rows on benches or tables, each table having two rows mounted thereon, both rows being driven from a single power shaft extending between the rows 10 below the table. The operators sit along the edges of the table facing the machines, and the row of operators on one side of the table faces the row of operators on the other side of the table.

This arrangement requires a direction of rotation of the machines of one row that is opposite 15 to that of the machines in the other row, and consequently necessitates a different arrangement of belting for driving the machines of one row to that for driving the machines of the other row.

20 Heretofore it has been customary to use a straight belt drive for one row, and a crossed belt drive for the other row. The latter form of drive involves wear on the belts, as the portions of one 25 stretch of the belt rub against the other. This wear is particularly great when the belt joint passes over the contacting portions of the belt going at high speed in the opposite direction. Belt breakage is frequent, resulting in costly cessation of production and in repair and replacement costs. If repair is attempted a belt is produced that is joined together in more places than one, and each extra joint increases the rapidity 30 of wear and the frequency of breakages and stoppages.

35 Among the general objects of my invention is therefore the provision of an arrangement for transmitting power to sewing machines whereby greater efficiency of operation and maintenance may be attained.

It is a further object of my invention to provide a power transmission unit adapted for ready association with a sewing machine.

It is also an object of my invention to provide 40 a power drive for sewing machines that permits a convenient adjustment to suit varying conditions.

These objects and such other objects as will 45 hereinafter appear or be pointed out are attained by the illustrative embodiment of my invention shown in the drawing, wherein:

Figure 1 is a sectional view, taken transversely through an installation comprising a double row of sewing machines driven from a common power shaft;

Figure 2 is an elevational view, on an enlarged scale, of a transmission unit as used for the machines of one of the rows of Figure 1; and

Figure 3 is an end view of the unit of Figure 2 as viewed from the right.

5 Referring now to the drawing for a detailed disclosure of the illustrative embodiment of my invention shown therein, it will be observed that the numeral 10 designates a sewing machine that is representative of one row of machines, while the 10 numeral 12 designates a sewing machine representative of a second row of machines. The machine 10 is mounted on a table section 14 and the machine 12 on a table section 16 and these table sections are shown as bridged by a trough or 15 channel 18.

Underneath the trough 18 is shown a power shaft 20, that drives a countershaft 22 positioned below the table section 14, by means of a belt 24 passing over suitable pulleys, and also drives 20 a countershaft 26 positioned underneath the table 16, by means of a belt 28 passing over suitable pulleys.

If the power shaft 20 rotates in a clockwise direction (as indicated by the arrow) the countershafts 22 and 26 will also rotate clockwise. The machine 10 is shown as having its driving 25 pulley 30 connected to the drive pulley 32 on the countershaft 22 by a straight belt drive 34, so that the pulley 30 will also rotate clockwise.

30 It is desired to drive the pulley 36 of the machine 12 in a direction opposite to that of the machine 10. The direction of rotation for the installation shown in the drawing must therefore be counter-clockwise. The arrangement for so 35 doing will now be described.

35 Mounted on the bench section 16 is shown a frame 38 carrying two pulleys 40 and 42. These pulleys are mounted in spaced relation, and one of them, 42, may be positioned at a higher level 40 than the other, for a purpose that will presently appear. The pulleys are shown as having their peripheries grooved whereby they are adapted to receive the conventional round belting customarily used on installations of this type.

45 One of the pulleys, 40, is shown as adjustable mounted on a stub shaft passing through a slot 44 in the frame 38, whereby its distance from the other pulley may be varied. The other pulley, 42, is shown as mounted on a stub shaft 48, fixedly 50 positioned in the frame 38, although it will be understood that if desired, for the purpose of securing extra adjustment, the stub shaft 48 may also be adjustable in the frame 38.

An endless belt 50 is shown as passing from the 55

drive pulley 52 on the countershaft 26 over the pulley 42, under the pulley 36 of machine 12, over the pulley 40 and back to the pulley 52. This, it will be observed, causes the counterclockwise movement of the pulley 36 of the machine 12, as desired, without any crossing of the belt 50, whereby the wearing away of the belt, due to crossing, is avoided.

It will be observed that the pulleys 40, 36 and 10 42 are so positioned that the pulley 36 presses the belt 50 inward between the pulleys, whereby a larger arc of contact and better traction are secured.

It will further be observed that the tension 15 of the belt may be readily adjusted by shifting the position of the stub shaft 44 of pulley 40, by the arrangement already described.

By positioning the pulley 42 higher than the pulley 40 it is possible to readily disengage the 20 pulley 36 of the machine from the belt 50. Where the base plate of the sewing machine is pivotally secured to the table, as for instance by a hinge 54, disengagement may be effected by merely lifting the machine about its hinge, whereby its 25 pulley 36 may assume a position 36'. Thereby ready access for repairs or inspection is attained.

The location of the parts might also be made such as to permit the sewing machine to be slid 30 backward and out of engagement with the belt 50. This might be effected by slightly lowering the position of pulley 40.

In order to shield the operator I have shown the frame 38 as provided with a guard or shield 54 covering the upper front portion of the pulley 42 in front of the operator.

It will be observed, after the principles of my 5 invention are fully understood, that my invention is not necessarily restricted to sewing machines, but that, as to certain phases thereof, it may have other applications.

Having thus described my invention, and illustrated its use, what I claim as new and desire to secure by Letters Patent is:

In combination, a pair of opposed tilttable frames, a first and a second driven pulley on said frames, respectively, a single driving pulley, 15 means including belts for driving the first driven pulley in the same direction as that of the driving pulley, and means for driving the second driven pulley in a direction opposite to that of the first driven pulley, said means including a 20 pair of spaced idler pulleys, belt means encompassing said idler pulleys and said driving pulley to cause rotation of said pulleys in the same direction, the said second driven pulley being adapted to frictionally engage the flight of the 25 belt means between said idler pulleys, means mounting one of said idler pulleys at a lower level than said second driven pulley whereby the latter may be disengaged from said belt means upon tilting of its supporting frame. 30

EMANUEL FISCHBACH.
